[57] CLAIM

The ornamental design for a self-supported mirror, as shown and described.

DESCRIPTION

FIG. 1 is a front perspective view of a self supported mirror showing my new design;

FIG. 2 is a rear perspective view thereof;

FIG. 3 is an enlarged front view thereof;

FIG. 4 is an enlarged rear view thereof;

FIG. 5 is an enlarged top view thereof;

FIG. 6 is an enlarged bottom view thereof;

FIG. 7 is an enlarged right side view thereof, the left side being a mirror image;

FIG. 8 is a front perspective view of a second embodiment of the design of FIG. 1;

FIG. 9 is a rear perspective view of FIG. 8;

FIG. 10 is an enlarged front view of FIG. 8;

FIG. 11 is an enlarged rear view of FIG. 8;

FIG. 12 is an enlarged top view of FIG. 8;

FIG. 13 is an enlarged bottom view of FIG. 8;

FIG. 14 is an enlarged right side view of FIG. 8, the left side being a mirror image.
